UNITED STATES PATENT OFFICE.

LANSING Onderdonk, of New York, N. Y., assignor to UNION SPECIAL MACHINE COMPANY, of Chicago, Illinois, a corporation of Illinois.

FABRIC GUIDING AND UNCURLING DEVICE.

1,282,458.

Specification of Letters Patent. Patented Oct. 22, 1918.

Application filed October 28, 1913. Serial No. 797,776.

To all whom it may concern:

Be it known that I, LANSING Onderdonk, a citizen of the United States, residing at New York, in the county of New York, State 5 of New York, have invented certain new and useful Improvements in Fabric Guiding and Uncurling Devices, of which the following is a description, reference being had to the accompanying drawing and to the figures of reference marked thereon.

The invention relates to new and useful improvements in fabric guiding and uncurling devices for overseaming machines, and more particularly to an overseaming machine 15 in which the fabric being stitched is supported and fed through the machine in substantially a vertical plane by intermittently rotating the feed wheels.

An object of the invention is to provide a 20 fabric guiding and uncurling device which is so mounted that it can be adjusted transversely of the plane of feed of the fabric so as to properly position said guiding and uncurling device for fabrics of different thickness.

A further object of the invention is to provide a support for a guiding and uncurling device of the above character which permits said guiding device to be adjusted vertically so that the edge of the material may be fed into a higher or lower line, as desired, so as to increase or decrease the width of the overseam.

A further object of the invention is to 35 provide a support for an uncurling device of the above character whereby said uncurling device may be moved toward and from the stitching point.

These and other objects will in part be 40 obvious and will in part be hereinafter more fully disclosed.

In the drawings, which show by way of illustration, one embodiment of my invention,

45 Figure 1 is a front view of an overseaming machine embodying my improvements.

Fig. 2 is an enlarged detail view in side elevation showing the relation of the fabric guiding and uncurling device to feed wheels.

50 Fig. 3 is a similar view showing the fabric guide and uncurling device from the opposite side.

Fig. 4 is a detail view showing the manner of adjusting the guide laterally or transversely of the plane of the fabric.

Fig. 5 is a detail view showing the adjustable stop by which the guide is adjusted toward and from the stitching point.

The invention is especially adapted for an overseaming machine which is provided with feed wheels 1 and 2, which feed wheels support and feed the fabric in substantially a vertical plane. The feed wheel 1 is carried by a shaft mounted in a suitable bracket 3 attached to the main casing 4 of the machine. The feed wheel 2 is mounted on a feed shaft journaled in a bracket 5, which is preferably pivoted at its lower end so that the feed wheels may be moved toward or from each other. The bracket 5 is yieldingly forced in a direction so as to hold the feed wheels in contact with the fabric. Said bracket may also be moved in the opposite directions manually when it is desired to insert a fabric or remove the same from a machine. A needle is carried by a needle bar 7 and reciprocates in a substantially horizontal plane above the feed wheel. A looper cooperates with this needle to form an overseaming stitch, and said looper is mounted and operated in the usual manner.

The layers of fabric F to be overseamed are passed between the feed wheels in substantially a vertical plane and said layers of fabric are gripped by the feed wheels and supported and intermittently fed to the needle. As shown in Fig. 2, the fabric projects above the feed wheels so that the needle may pass through the superposed edges of the fabric and the looper thread led over the edge of the fabric.

The fabric is led to the feed wheels through a fabric guiding and uncurling device 7. Said fabric guiding device consists of a central bar 8 which extends downwardly to a point beneath the upper face of the feed wheels. The lower end of this bar 8 is reduced so as to form a thin web and the layers of fabric are led to the feed wheels one on each side of the web. An uncurling plate 9 is pivoted at 10 to a pair of lugs carried by the bar 8. An uncurling plate 11 is also pivoted to the bar, as at 12, and these two uncurling plates 9 and 11 engage the outer face of the fabric and cooperate with the central web of the bar 9 in uncurling the fabric and guiding the same.

A spring 13 is located between the upper ends of the plates 9 and 11 and normally presses the lower ends of these plates in a

direction toward the central web. A bolt 14 is carried by the bar 8 and thumb-nuts 15 and 16 carried by said bolt bearing against the outer faces of the plates 9 and 11, respectively, limit the inward movement of the lower ends of the plates toward the web. The uncurling plates 9 and 11 project forwardly in the line of feed, as clearly shown in Fig. 1, and coöperate with the forwardly projecting part 17 on the central web of the bar 8. A pin 18, carried by the central web, projects from each side thereof and extends through openings in the uncurling plates 9 and 11. This pin guides the plates 9 and 11 and also prevents the fabric from creeping up too high between the plates.

The bar 8 is pivoted at 19 to a supporting head 20. This supporting head 20 is clamped to a plate 21 which in turn is mounted on a bracket 22 bolted to the main casing of the machine. The plate 21 is a right angle plate and the horizontal member 23 thereof is provided with slots, through which screws 24 pass. These screws 24 extend into the bracket 22 and serve to adjustably hold the plate 21 on the bracket. The slots are so formed that the plate 21 may be moved longitudinally of the upper open end of the bracket 22, and this movement of the plate 21 will move the fabric guiding and uncurling device in a direction substantially at right angles to the plane of travel of the fabric. The bracket 22 is secured to the main casing by clamping screws 25. These screws pass through slots 25^a in the bracket so that said bracket may be adjusted vertically on the screws and this vertical adjustment of the bracket raises and lowers the fabric guiding and uncurling device and permits the edges of the fabric being stitched to project more or less above the feed wheels. This adjustment of the fabric guide and the edge of the fabric increases or decreases the width of the overseam.

The bar 8 is loosely mounted on the supporting head 20 and swings by gravity to the position shown in Fig. 1. In this position, the rear edge of the bar rests against an adjustable bolt 26 which is carried by a bracket 27 attached to the supporting head 20. This bracket has spaced walls 28 and 29 between which the bar rests against the end of the adjustable bolt. The feed of the fabric also draws the bar against this bolt. By adjusting the bolt, the position of the fabric guide and uncurling device relative to the stitching point may be varied. It is desirable that this fabric guiding or uncurling device shall be as close to the stitching point as possible without interfering with the free feed of the fabric by the feed wheels.

It will be obvious that when a heavy fabric is being stitched the fabric guiding and uncurling device must be positioned a greater distance from the stitching point.

This can be readily accomplished by adjusting the bolt above described. When a thicker fabric is being stitched, the fabric guiding and uncurling device must also be adjusted laterally so as to keep the central web in a plane midway between the feed wheels when said feed wheels are in action. This may be accomplished by adjusting the plate 21 on the bracket 22.

The bar 8 may be held in raised position 75 by a latch 30 which is pivoted to a projecting ear 31 formed on the center bar 8 and this latch coöperates with the notched supporting head 20. Said head 20 is also provided with notches which may be engaged 80 by the latch for holding the fabric guiding and uncurling device in inoperative position.

A spring 32 normally forces the latch into contact with the supporting head 20.

85

In order to facilitate the adjustment of the bracket 22, I have provided an adjusting screw 33 which is threaded into the casing 4 and is provided with a groove in its head to receive a lug 34 carried by the bracket 22. This screw turns freely in the lug 34 and by turning the screw in one direction after loosening the clamping screws 25, the bracket may be adjusted to raise the guide, and by turning the screw 95 in the other direction it may be lowered. In a device where the adjustment is vertical, this adjusting screw is of considerable importance as otherwise when the clamping screws 25 are released the bracket would 100 drop by gravity. Then again, this adjusting screw enables fine adjustments to be made which are desirable.

From the above description, it will be apparent that I have provided a fabric guiding and uncurling device which is so supported that it may be readily and quickly adjusted to position the same for operating upon different thicknesses of fabric and for also increasing or decreasing the depth of 110 the overseam.

Having thus described my invention, what I claim is:

1. The combination with supporting feed wheels, of a fabric guide for guiding the fabric to the feed wheels, said fabric guide comprising a central bar having a web extending between the layers of the fabric, uncurling plates carried by said central bar and engaging the outer faces of said layers 120 of fabric, and means for supporting said fabric guide including a supporting head, a bracket carried by said supporting head having spaced walls between which the center bar of the fabric guide rests when said guide is in normal operative position, and an adjustable bolt extending between said spaced walls and against which said bar of the fabric guide rests.
2. The combination of devices for sup- 125

porting and feeding a fabric in substantially a vertical plane, a guide through which the fabric passes to the feeding devices, a bracket adjustably attached to the supporting casing and supporting said guide, screws for clamping said bracket in adjustable positions, and an adjusting screw for supporting and shifting the position of

the bracket when released by its clamping screws. 10

In testimony whereof, I affix my signature in the presence of two witnesses.

LANSING ONDERDONK.
